UNITED STATES PATENT OFFICE.

WILLIAM M. WHITE, OF BRISTOL, VIRGINIA.

SHOE-HEEL.

1,121,436.

Specification of Letters Patent. Patented Dec. 15, 1914.

Application filed November 6, 1913. Serial No. 799,542.

To all whom it may concern:

Be it known that I, WILLIAM M. WHITE, a citizen of the United States, residing at Bristol, in the county of Washington and State of Virginia, have invented certain new and useful Improvements in Shoe-Heels; and I do declare the following to be a full, clear, and exact description of the invention, such as will enable others skilled in the art to which it appertains to make and use the same.

This invention relates to improvements in shoe heels and more particularly to those having detachable heel pads.

15 The primary object of the invention is to provide a device of this character which will be simple, strong, and efficient in operation and which will present a neat appearance on a shoe.

20 A secondary object is to provide means for securely retaining the removable pad on the heel and yet render it readily detachable when desired.

Still another object is to provide a guide 25 for the removable pad, of such construction as to render it readily applicable as an anti-slipping device, when the pad is removed.

With these objects in view the invention resides in certain novel features of construction and combination herein described and claimed and shown in the drawings, wherein:

Figure 1 is a side elevation of part of a shoe showing the application of my invention, Fig. 2 is a vertical sectional view of a portion of the shoe on a line 2—2 of Fig. 1 showing an inner end view of the heel, Fig. 3 is a central vertical longitudinal section of the heel, Fig. 4 is a bottom plan view of the removable pad guide, and Fig. 5 is a detail horizontal sectional view showing the position of parts when the retaining screws are being inserted.

In the accompanying drawings, the numeral 1 designates a shoe of any suitable shape and 2 the usual heel thereon.

Secured to the bottom of this heel in any suitable manner such as by the screws 3 is a metal plate 4 having a downwardly projecting U-shaped flange 5 undercut as at 6 on its inner side and beveled as at 7 on its lower edge. Screw holes 8 are disposed at suitable intervals through the flange 5.

Adapted for insertion within the U-shaped guide 5 is a dove tail leather tongue 9 secured in any suitable manner to the heel pad 10 which may be constructed of rubber or other yielding material. The edges of the dove tail tongue 9 are provided with screw holes 11 which are disposed slightly in advance of the screw holes 8 in the guide 5.

With this construction, the dove tail tongue 9 is slipped into the U-shaped guide 5 and when in this position, as before stated, the holes 11 will be slightly in advance of 65 the holes 8. Tapered screws 12 are then inserted through these holes 8 and 11, and by so doing, it will be readily seen that the dove tail tongue 9 will be forcibly engaged with the rear end of the U-shaped guide 5. 70

By beveling the under side of the U-shaped guide as at 7, I provide a very simple, yet efficient, anti-slipping device which may be used when the pad 10 is removed and which will be covered and protected 75 when said pad is in position within said guide.

I wish it further understood that the beveled lower end of the flange 5 likewise acts as a thrust bearing for receiving all lateral 80 thrust exerted on the pad 10, since said flange is of greater height than the thickness of the tongue 9 and is beveled downwardly and outwardly from said pad to its outer edge, the pad 10 projecting laterally beneath 85 said beveled lower end of the flange and being shaped to conform to the bevel thereof. Without this construction, the lateral thrust exerted upon the pad 10 would be directly imparted to the tongue 9, thereby tending to 90 dislodge the same from its engagement with the undercut flange 5.

I claim as my invention:

The combination with a shoe heel of a metal plate secured to the lower side thereof, 95 a U-shaped flange depending from the rear and side edges of said plate and having its inner side undercut, a dove-tail tongue embraced by said flange and contacting at its side and rear edges and with the undercut 100 inner side thereof, said tongue being of less thickness than the height of the flange and the latter being beveled downwardly and outwardly from said tongue to its outer edge to provide a thrust bearing, and a pad secured to the tongue and projecting laterally 105

therefrom beneath the flange, the upper corner of said laterally projecting portion of the pad being beveled and contacting with the beveled lower edge of said flange, whereby lateral thrust exerted upon the pad will be imparted to said lower edge of the flange.

In testimony whereof I have hereunto set

my hand in presence of two subscribing witnesses.

WILLIAM M. WHITE.
